UNITED STATES PATENT OFFICE.

JAMES CARAFILIDIS, OF SABRATON, WEST VIRGINIA, ASSIGNOR OF ONE-FIFTH TO
VASEL SAVIDIS, OF MORGANTOWN, WEST VIRGINIA, AND THREE-TENTHS TO
JAMES DELAS, OF GREENSBURG, PENNSYLVANIA.

TIN-OPENING MACHINE.

Application filed February 27, 1923. Serial No. 621,643.

To all whom it may concern:

Be it known that I, JAMES CARAFILIDIS, a subject of Greece, and resident of Sabraton, county of Monongalia, and State of West Virginia, have invented certain new and useful Improvements in Tin-Opening Machines, of which the following is a specification.

This invention relates broadly to tin opening devices and more specifically to a power apparatus for separating metal sheets which have been caused to closely adhere through rolling in a pack.

The primary object of the invention is to provide a power mechanism whereby rolled metal plates or sheets which have become more or less closely bonded in the pack rolling process may be quickly and conveniently separated or stripped apart.

A further object is to provide a comparatively simple, durable and inexpensive machine for effecting the forcible separation of bonded sheets.

With these and other objects in view, the invention resides in the features of construction, arrangement of parts and combination of elements, which will hereinafter be fully described, reference being had to the accompanying drawings, in which—

Figure 1 is a front elevation of the invention, one of the tongs-closing members being shown in section;

Figure 2 is a cross section of the same taken on line 2—2, Fig. 1;

Figure 3 is a partial longitudinal section taken substantially on line 3—3, Fig. 2; and—

Figure 4 is an end elevation of the upper portion of the machine, showing one of the supporting arms for the bar upon which the tongs-closing members travel.

Referring to said drawings, 1 and 2 indicate upper and lower horizontal guide bars which are rigidly carried in opposing parallel relation by a suitable frame 3 supported by legs 4. Mounted between and disposed in tongue and groove relation with said bars 1 and 2 are two slide-blocks 5 which are reciprocable longitudinally into

and out of meeting, or substantially meeting, relation at or adjacent to a midway point with respect to the opposite ends of said bars. Each of said slide blocks has

mounted stationarily thereon, as by means of bolts or rivets 6, one member 7 of a pair of tongs, and pivoted to said member 7 is the other member 8, said members being disposed in crossed relation and having cooperating jaws 7^a and 8^a formed on their lower ends.

The two pairs of tongs are designed to be initially disposed in approximately meeting relation and to receive between the jaws thereof the upper edges of adhering or bonded sheets which are to be separated, following which said jaws are closed into tight-gripping relation to such sheets, and the blocks carrying the tongs are then actuated to move in opposite directions for forcibly stripping said sheets apart.

The upper ends of the members 7 and 8 of each pair of tongs are normally separated a distance allowing the jaws thereof to remain open for the reception therebetween of the edge of a sheet. Overhanging said upper ends of each tongs is a vertically reciprocable device whereby closing of the tongs may be effected, said device comprising a block 9 having therein an upright conical or bell-shaped socket 10. Upon lowering said device upon the upper ends of the underlying tongs members, said ends are engaged by the curved or inclined socket walls and the pivoted member 7 is forcibly actuated to swing toward the other member 8 for closing the jaws of the tongs. Anti-friction rollers 11 are carried by the upper ends of the tongs members for minimizing frictional resistance to lowering of the blocks 9 to tongs-closing position.

Said blocks 9 are mounted for longitudinal travel upon a bar 12, preferably of rectangular form in cross section, each block being preferably provided with upper friction-reducing rollers 13 and lower rollers 14 for engaging the top and under sides, respectively, of said bar. Said bar has its opposite ends pivotally mounted upon the outer ends of crank-arms 15 which are fixed upon a shaft 16 that is mounted for rotary movement on upright bearing brackets 17 carried by the frame 3.

A lever 18 fixed upon the shaft 16 is manually operable for rotating said rod forward to effect lowering of the bar 12 and, consequently, depression of the blocks 9 to

- tongs-closing positions. A dog 19 formed upon the end of a spring-pressed rod 20 is normally disposed in engagement with a stationarily mounted rack segment 21 and 5 is designed to maintain said shaft in adjusted position against the tendency to return to block-elevating position, actuated by a weighted rearwardly-extending arm 22 carried by said shaft. Said rod 20 is carried by said lever 18 and has connection through pivoted links 23 and 24 with a shifting lever 25 whereby it may be actuated for withdrawing the dog 19 from engagement with the rack segment.
- 10 15 The slide-blocks 5 may be actuated to travel back and forth by any suitable power mechanism, the mechanism herein shown comprising air cylinders 26 mounted on opposite ends of the frame 3. A piston 27 disposed for reciprocation in each of said cylinders is carried by a piston rod 28 which has its outer end suitably attached to the opposite slide-block. Pipes 29 and 30 provided for introduction of air under pressure into 20 25 opposite ends of each cylinder, it being understood that air is admitted into said ends alternately to effect reciprocation of the piston.
- 30 It will be understood that the tongs-closing blocks 9, being freely shiftably along the bar 12, are actuated to travel with the tongs with which they are operatively engaged and that, consequently, the jaws of said tongs are maintained in tightly gripping 35 relation to interposed edge portions of sheets during their travel.
- 40 A light coil spring 31 connecting the members 7 and 8 of each pair of tongs serves to maintain said members in such relation that their upper ends are at all times in position to be operatively engaged by the overlying blocks 9. However, said spring is not under sufficient tension to effect closing of the tongs.
- 45 50 As many changes in details of construction and many widely different embodiments of my invention, within the scope of the appended claims, may obviously suggest themselves to those skilled in the art, it is intended that all matter contained in the foregoing description and shown in the drawings shall be interpreted as illustrative and not in a limiting sense. Furthermore, the terms and expressions which are herein used

are employed as terms of description and 55 not of limitations.

What is claimed is—

1. A tin opening machine comprising a pair of horizontally disposed guide bars, blocks disposed for travel between said bars, 60 a pair of pivotally related sheet-gripping members carried by each block, said members having cooperating jaws at one end thereof, a socketed device superposed over the opposite ends of each pair of members, 65 means for depressing said devices to effect closing of said jaws, and power mechanism for actuating said blocks to and from substantially meeting relation.

2. A tin opening machine comprising two 70 pairs of vertically disposed tongs of pivotally related crossed-member type, each pair having cooperating jaws on the lower end thereof, the upper ends of the members of each pair of tongs carrying rollers, means 75 depressible into engagement with said rollers whereby said tongs members are moved relatively to close the jaws thereof, and means for actuating said pairs of tongs to move in opposite directions, said tongs-closing means 80 being arranged to travel with said tongs.

3. A tin opening machine comprising two horizontally movable sheet gripping devices, each embodying a pair of pivotally related jaw-carrying members, a block superposed 85 over the upper ends of the members of each gripping device, said block having an upright conical socket adapted to receive said upper ends of the members therein and being adapted through lowering thereof to effect movement of said members into jaw-closing relation, a rotary shaft disposed above said blocks, arms carried by said shaft, a bar carried by said arms, said bar having said blocks horizontally shiftable 95 thereon, means normally maintaining said shaft in a position holding said bar elevated, a lever whereby said shaft may be rotated to effect lowering of said blocks, and power mechanism for moving said gripping devices 100 in opposite directions.

In testimony whereof, I affix my signature in presence of two subscribing witnesses.

JAMES CARAFILIDIS.
